UNITED STATES PATENT OFFICE.

JOSEPH J. SHIRLEY, OF GRANBURY, TEXAS.

SPRING-FRAME FOR FREIGHT-CARS.

SPECIFICATION forming part of Letters Patent No. 235,462, dated December 14, 1880.

Application filed May 27, 1880. (No model.)

To all whom it may concern:

Be it known that I, JOSEPH J. SHIRLEY, of Granbury, in the county of Hood and State of Texas, have invented certain new and use-

ful Improvements in the Use of Springs in Transportation; and I do hereby declare that the following is a full, clear, and exact description of the invention, which will enable others skilled in the art to which it appertains to make and use the same, reference being had to the accompanying drawings, which form a part of this specification.

Figure 1 represents a longitudinal sectional view of a car equipped with my improved spring-padding. Fig. 2 is a similar view, showing a modification in the arrangement of the springs; and Fig. 3 is a view of one of the platforms resting upon or against springs and supporting the merchandise.

Corresponding parts in the several figures are denoted by like letters of reference.

This invention relates to vehicles for the transportation of merchandise; and it consists in providing such vehicles with an interior spring-padding, and in some cases with intermediate elastic floors or partitions, by which injury to the load, by jolting while in transit, shall be prevented, and which shall further conduce to the preservation of fruits and other merchandise of a like perishable nature, by causing a forced circulation of air around the packages of goods, as will be hereinafter more fully shown and described.

My invention, the nature of which renders it specially adapted for railroad freight-cars, is fully illustrated in the accompanying drawings, where A represents the body of an ordinary box-car. B B are frames, suitably constructed of wooden or metallic slats, or both, and supported upon springs C C, which may be coiled, elliptical, or of any other suitable kind. If desired, the frames may be connected in pairs by said springs, as shown in the drawings, thus forming, practically, spring-matresses, which may be conveniently handled and placed in position.

These spring padding-frames are placed in the bottom, at the ends and sides, and even under the roof of the car. The positions may be varied according to the kind and class of

merchandise to be transported, which said merchandise is then packed in the car, where it is supported upon, between, and under the said spring-frames.

Between the several rows, tiers, or piles of crates, boxes, or other packages of merchandise, separate spring-frames, D, may be interposed, as shown in Fig. 2, in a horizontal or vertical position, as the case may require.

I provide the frames B with slats or clamps E, adjustable by thumb-screws F, to clamp and hold the crates or other packages securely in position while in transit, and at the same time enable air to circulate freely between them.

From the foregoing description, taken in connection with the drawings hereto annexed, the operation and advantages of my invention will be readily understood.

The spring-frames upon which the merchandise is supported prevent injury thereto by jolting while in transit, while at the same time the easy swinging motion, and the fact that the several packages are spaced from each other, tends to promote a free circulation of air, which, especially if the air be artificially cooled, greatly assists in preserving perishable goods from destruction.

The spring-frames are simple, cheap, and easily applied to box-cars of the ordinary construction.

I am aware that freight-cars have been provided with movable bottoms supported on springs resting beneath upon the timbers of the main car-frame. This, however, I do not claim; but,

Having thus described my invention, I claim and desire to secure by Letters Patent of the United States—

The combination, with a vehicle for the transportation of merchandise, of the spring padding-frames B, having adjustable slats or cleats E, as and for the purpose set forth.

In testimony that I claim the foregoing as my own I have hereto affixed my signature in presence of two witnesses.

JOSEPH J. SHIRLEY.

Witnesses:

B. M. ESTES,

W. A. DUKE.
